UNITED STATES PATENT OFFICE.

EDMUND OCUMPAUGH, 2d, OF ROCHESTER, NEW YORK.

ADDING ATTACHMENT FOR CHECK-PRINTERS.

1,134,551.

Specification of Letters Patent.

Patented Apr. 6, 1915.

Application filed May 15, 1914. Serial No. 838,756.

To all whom it may concern:

Be it known that I, EDMUND OCUMPAUGH, 2d, a citizen of the United States, and resident of Rochester, in the county of Monroe and State of New York, have invented certain new and useful Improvements in Adding Attachments for Check-Printers, of which the following is a specification.

This invention relates to machines for printing numerical amounts, and particularly to machines of the kind known as "check-writing" or "check-printing" machines, by which the amounts are filled in on bank-checks.

The object of the invention is to provide a machine, of the type in question, with simple and reliable mechanism for adding and registering the sum of the various numbers or amounts printed by the machine.

In producing adding-mechanism for a machine such as a check-printing machine, in which decimal numbers of several places are printed, special provision is necessary for carrying from one of the adding-wheels to another, owing to the fact that these adding-wheels must be rotated not only by the carrying-mechanism, but also directly in accordance with the positions of the corresponding type-wheels of the printing-machine, so that the ordinary gear-connections for carrying from one adding-wheel to the next cannot be used.

Accordingly, one feature of the present invention resides in novel carrying-mechanism for actuating the adding-wheels independently of the mechanism by which the adding-wheels are rotated in accordance with the positions of the type-wheels, and at a different time.

In a check-printing machine the printing-types are first set to the proper position for the required amount by one manual operation, and the impression from the types is then caused by a distinct manual operation.

It is not practicable to coördinate the adding-mechanism with the type-carrier in such a way as to cause the adding-mechanism to register in consequence of the setting or selective movement of the type-carriers, for the reason that the type-carriers are not moved back to zero, or to any definite point, after each printing operation, and for the further reason that it is not always convenient, in setting the type-carriers, to move them immediately and exactly to the required position.

Accordingly, another object of the invention is to so connect the adding-mechanism with the type-carriers that the adding-mechanism shall not register the amount of the selected types upon the type-carriers until the production of an impression from these types. To this end, I employ adding-mechanism so constructed and arranged that while the extent of movement imparted in each instance to the adding-wheels is determined in accordance with the position occupied at the moment by the type-carriers, the power for so moving the adding-wheels is derived from the impressing-mechanism.

In a check-printing or similar machine the impressing operation is often performed by subjecting a lever or other manually-operable part to a sudden and severe pressure or blow, and therefore, if the impressing-mechanism were connected positively and rigidly with the adding-mechanism, so as to move the latter directly during the impressing operation, the movement imparted to the adding-mechanism would be too rapid and severe, so as to cause either injury to the mechanism, or over-running of the adding-wheels.

Accordingly, another object of the invention is to avoid such sudden and severe operation of the adding-mechanism, and for this purpose I employ, in the first place, an arrangement in which the impressing-movement of the impressing-mechanism is not employed to actuate the adding-mechanism, but the latter is actuated partly by spring-controlled means, which are merely released during the impressing-movement, and partly by power derived directly from the impressing-mechanism, but during the return-movement of the latter. For the same purpose I employ motion-retarding means, such as a dash-pot, for retarding this return-movement to a speed at which the adding-mechanism may be safely operated.

Other objects of the invention, and the features of construction and arrangement by which the several objects are attained, will be set forth in connection with the following description of the illustrated embodiment of the invention.

In the accompanying drawings: Figure 1 is a front-elevation of a check-printing machine embodying the present invention, with parts broken away to show the interior mechanism; Fig. 2 is a vertical section on the line 2—2 in Fig. 1; Fig. 3 is a partial

sectional view of the adding mechanism, taken on the line 3—3 in Fig. 2, but on a larger scale; Fig. 4 is a vertical section on the line 4—4 in Fig. 3; and Fig. 5 is a front-elevation of a portion of the adding-mechanism, comprising two of the adding-wheels and certain parts immediately associated therewith.

The invention is illustrated as embodied 10 in a check-printing machine of which the general form and construction are not novel. This machine has a horizontal shaft 6, journaled in a casing 7 and carrying a series of type-wheels with peripheral types which 15 may be brought selectively beneath a central opening in a work-supporting plate 8, which forms the top of the casing. The check-blank or other work is forced downwardly, against the types which are in operative position, by means of a platen 9, which may be depressed for this purpose by a hand-lever 10. In this manner the paper is pressed 20 against the types and is printed thereby, the types being supplied with ink by the usual ink-rollers bearing against the peripheries 25 of the type-carriers, as they are rotated into operative position.

The illustrated machine is what is commonly described specifically as a "check-writing machine," that is to say, a machine 30 that is adapted to fill in the amount of a check not only by figures but also by words. Accordingly, it is provided with four type-carriers 11, 12, 13 and 14, in the form of 35 drums or wheels, the wheel 11 bearing types expressive of even numbers, up to one hundred, in words, the wheel 12 having corresponding numbers in figures, the wheel 13 bearing the word "Dollars" and various 40 fractions of a dollar from 00/100 to 99/100 in figures, and the wheel 14 having the corresponding amounts in figures expressed 45 decimaly. Thus, for example, the machine is arranged to print a check in the following form: "Eighty-four & 34/100 Dollars"—\$84.34." It is, accordingly, necessary 50 that the wheels 11 and 12 be rotated always in unison in setting the machine for any required amount, while the wheels 13 and 14 must also be rotated in unison, but 55 independently of the wheels 11 and 12. The movements of the wheels 11 and 12 are controlled by a manually-rotatable member 15 fixed on the end of the shaft 6, the position 60 of the wheels being indicated by a graduated index-wheel 16, which turns with the shaft, and which is viewed through a member 117 fixed to the casing and forming a sight-opening. The wheel 11 is keyed directly to 65 the shaft 6 so as to turn therewith. The wheel 12 is not fixed to the shaft, but turns loosely upon a sleeve 17, which also turns loosely on the shaft, and which is connected with the manually-rotatable member 18 by 70 which the wheels 13 and 14 are set. Both of

the wheels 13 and 14 are keyed directly to the sleeve 17 so as to turn therewith, and their position is indicated by an index-wheel 19 and sight-opening 20 at the right-hand side of the machine.

Since the wheel 12 must be mounted upon the sleeve 17, in order to interpose it between the wheels 13 and 14, it cannot be fixed to rotate directly with the shaft 6, and accordingly its movements are coördinated 75 with those of the wheel 11 by gear-connections with the latter. For this purpose the wheel 12 is provided with an annular series of gear-teeth 21 which engage a pinion 22 fixed on a counter-shaft 23 journaled in the 80 casing of the machine, and this counter-shaft carries a second pinion 24, which meshes with gear-teeth 25 on the type-wheel 11.

To assist in setting the type-wheels exactly in any required position, they are provided with detent-mechanism for arresting them in a position in which one or another of their types are exactly beneath the platen 9. For this purpose each of the wheels 11 and 13 is provided with an annular surface 90 26, provided with rounded projections and depressions corresponding in position with the rows of type, and these surfaces are engaged by spring-pressed sliding detent-members 27 mounted in the casing, as shown in 95 Fig. 2.

The types are inked by any ordinary or suitable means and for this purpose an ink-roller 28 is shown in Fig. 2, mounted in the casing in position to engage the types as the 100 corresponding type-wheel is rotated, and it will be understood that similar ink-rollers are employed in connection with each of the type-wheels.

The adding-mechanism comprises a series 105 of adding-wheels mounted upon a shaft 30, which is fixed in horizontal position in the casing 7 of the printing-machine. The first of these wheels 31 indicates amounts in cents from 0 to 9, the second adding-wheel 32 indicates cents in amounts from 10 to 90, the third adding-wheel 33 indicates dollars in amounts from 0 to 9, the fourth wheel 34 indicates dollars in amounts from 10 to 90, and the fifth wheel 35, and any desired number 110 of other adding-wheels connected in series therewith, indicate sums in dollars up to any required amount, according to the number of wheels provided, these wheels having numerals on their peripheries, as 115 shown in Fig. 5, and the numerals being visible at the front of the machine through openings 36 in the casing.

The means for transferring to the adding-wheels the amounts impressed from the corresponding type-wheels are as follows: Alongside each of the adding-wheels 31, 32, 33 and 34, a pinion 37 is journaled on the shaft 30, this pinion, for the sake of compactness and to afford a bearing of suitable 120 130

width, having a hub which extends into and forms a bearing for the hub of the adding-wheel, although the pinion and the wheel are independently rotatable. The pinion 37 is provided with a lug 38 in which a spring 39 is fixed, this spring being shaped to adapt it to operate in the manner of a pawl in connection with a series of ratchet-teeth 40 integral with the adjacent adding-wheel. Accordingly, when the pinion is rotated in a clockwise direction, as the parts are shown in Figs. 2 and 4, the adding-wheel is caused to rotate with it, whereas movement of the pinion in the opposite direction causes the spring 39 to pass idly over the ratchet-teeth, and retrograde movement of the adding-wheel at this time is prevented by a spring 41 (Fig. 2) which co-operates, in the manner of a pawl, with a knurled portion 42 of the periphery of each adding-wheel.

Each pinion 37 is actuated by a gear-segment 63, which is journaled on the sleeve 17, as shown in Fig. 2. Each segment is provided, at its rear extremity, with a pin 44 which co-operates with an arm 45, fixed upon a rock-shaft 29 which is journaled in the casing 7. This rock-shaft is actuated by means of an arm 46, which has a pin-and-slot connection with a rod 47 extending upwardly at the rear of the machine. The rod 47 is pivoted at 48 to the rear end of the hand-lever 10 by which the platen 9 is actuated, this hand-lever being pivoted at 49, on an overhanging arm 50 extending over the work-support 8 of the machine. This arm 50 also provides a bearing for the plunger which carries the platen 9, the end 51 of this plunger engaging the lower surface of the lever 10, and the plunger and the lever being normally held in the position of Fig. 2 by a powerful spring 52.

When the forward end of the hand-lever 10 is depressed, to cause an impression, the rod 47 is raised, the rock-shaft 29 is rocked, and the arm 45 is depressed. At this time the gear-segment 63 is not directly actuated by its connections with the impressing-mechanism, but, through the disengagement of the pin 44 by the arm 45, movement of the segment is permitted under the influence of a spring 53 which is connected, at its upper end, with the pin 44, and fixed at its lower end to a horizontal rod 54 mounted in the casing. Accordingly, when the hand-lever is depressed the segment 63 is swung in a direction to rotate the pinion 37 counter-clockwise. Upon the termination of the impressing-movement, when the hand-lever 10 is released, the spring 52 returns the parts to normal position, thus causing the rock-shaft 29 to be rocked in the opposite direction so as to raise the arm 45 and cause it to engage the pin 44, whereby the gear-seg-

ment is swung back to normal position, and the spring 53 is again extended. Since this is the operative movement of the parts by which the adding-wheels are rotated, it will be apparent that the extent of movement of each adding-wheel depends upon the extent of the movement imparted to the corresponding gear-segment 63. This is determined automatically by stop-mechanism, which will now be described.

Two stop-plates 55 and 56 are fixed side by side upon the sleeve 17, so as to be rotated with the type-wheels 13 and 14, and two similar stop-plates 65 and 66 are fixed to the hub of the type-wheel 12. The stop-plates 55 and 65 are each divided into ten segments, of which each is provided with ten steps 57 at graduated radial distances from the axis of the stop-plate, the ten spaces in each segment corresponding to the ten digits, in the units place on the wheel 12 or 14, associated with each digit in the tens place on the same wheel. A stop-pin 58 is mounted in the upper end of a link 59 pivoted to each gear-segment 63, associated with the adding-wheel 31 or 33, and one end of this pin is guided in a vertical slot in one of a series of cross-bars 60 fixed in the casing 7, while the other end of each stop-pin co-operates with one of the stop-plates 55 or 65. Accordingly, the idle movement of the gear-segment 63 is limited in extent by the engagement of the stop-pin with one or another of the steps 57, so that upon the return-movement of the gear-segment the rotation imparted to the adding-wheel 31 or 33 is proportionate to the amount of the significant digit in the units place on the type-wheel 14 or 12, that is to say, to the amount expressed by the digit which is in position to produce an impression upon the check blank. In Fig. 2 the parts are in such position that the stop-pin will engage the uppermost step 57 on one of the segments of the stop-plate 65, and as this is the step corresponding to zero, no movement of the gear-segment will occur upon the performance of an impressing operation, and therefore the adding-wheel 33 will receive no rotation.

The adding-wheels 32 and 34 are moved by means analogous to those employed to actuate the wheels 31 and 33, but in this case the stop-pin 61 co-operates with the stop-plate 56 or 66. The gearing and ratchet-mechanism are similar in all respects to those already described. Since the amounts of the digits in the tens places on the type-wheel 12 or 14 changes only at ten points about the periphery of the wheel, the stop-plates 56 and 66 have only ten graduated steps about their entire peripheries, as shown in Fig. 2.

Since the idle movements of the gear-seg-

ments 63 are produced by the springs 53 as above described, the speed of these movements is limited by the strength of the springs, which may be so adjusted as not to 5 produce an excessive speed. Since the operative return-movement of the gear-segment is caused by power derived from the spring 52 in the impressing-mechanism, and since this spring must have sufficient power to 10 move the parts with great certainty under all conditions, it is desirable to retard this return-movement to some degree, to prevent violent operation of the adding-mechanism, and accordingly I employ a dash-pot as 15 shown in Fig. 2, this dash-pot comprising a piston 67 which is pivoted to the lower end of the rod 47, and which moves in a cylinder 68 fixed to the back of the casing 7. Upon the upward movement of the piston air is 20 admitted to the cylinder through a check-valve 69, but the downward movement of the piston is resisted by the pressure of the air, so as to retard the return movement of the mechanism. This retardation may be ad- 25 justed by means of a valve 70 in the piston, controlling an escape-vent from the cylinder. In addition to retarding the return-movement imparted to the gear-segment 43, the dash-pot has the further advantage that 30 at the beginning of the return-movement of the impressing-mechanism it retards this movement sufficiently to permit the comple- 35 tion of the idle movement of the gear-segments by the springs 53, and for the same purpose the arms 45 are made to have a downward movement of greater amplitude than the maximum movement imparted to the pins 44 by the springs 53.

The carrying-mechanism associated with 40 the adding-wheels will now be described. Beneath each of the adding-wheels 32, 33 and 34 a bar 71 is arranged, this bar being slidingly mounted at its ends in bearings in the casing 7. A spring 72 connected with 45 each bar tends to draw it to its foremost position, and a spring-pressed pawl 73 pivoted on the bar engages a series of ten ratchet-teeth 74 formed on the adding-wheel 32, 33 or 34, so that at each forward move- 50 ment of the bar the wheel is rotated through one space. Each bar is moved rearwardly by means of one of a series of arms 75 loosely mounted on the rock-shaft 29, the arm having a lost-motion connection with the shaft 55 through a pin and slot 76, as shown by dotted lines in Fig. 2. The arms 75 engage pins 77 on the bars 71, and the action of the lost-motion connection is such that during the impressing movement of the machine the 60 first part of the rotation of the rock-shaft 29 has no effect upon the arms 75, but the latter part of this movement causes the arms 75 to swing rearwardly, thus moving the bars 71 rearwardly, if any of them happen to be 65 in forward position. When a bar 71 reaches

its rearmost position it is normally retained therein by means of a pawl 78 near the front of the machine, which engages a notch 79 on the bottom of the bar. In case the pawl 78, for reasons hereinafter described, is not 70 in position to arrest the bar, the bar is arrested by means of a spring-pressed pawl 80 near the rear of the machine, which en- 75 gages a notch 81 in the bottom of the bar. Each pawl 78 is fixed on a short rock-shaft 82, which is journaled in a fixed part of the frame of the machine, and each rock-shaft carries, at its other end, a trip-arm 83 which coöperates with a trip-pin 84 mounted on the adding-wheel 31, 32 or 33 as the case may be. This pin 84 is so located that it may en- 80 gage the corresponding trip-arm 83 when the adding-wheel which carries the pin arrives at a position in which the figure 9 upon it disappears from the sight-opening 36 and the figure 0 appears. This is the point at which a unit should be carried to the next succeeding adding-wheel. Accordingly, sup- 85 posing the impressing-movement of the ma- 90 chine to have been made during the succeed- 95 ing return-movement of the parts, each bar 71 will be held in its normal rearward position by the pawl 78, unless the adding-wheel be rotated, during this return-movement, sufficiently to bring the pin 84 into engage- 100 ment with the trip-arm 83. If this occurs the arm and the pawl 78 will be depressed, thus releasing the pawl from the slide-bar, and the bar will thereupon be moved for- 105 ward slightly by the spring 72, but will be momentarily arrested by the pawl 80, until the rotation of the adding-wheel 31, as de- 110 termined by the stop-plate 57 and the mech- 115 anism associated therewith, has been com- 120 pleted. As the impressing-mechanism finally reaches its normal position, however, the end of the arm 75 will be brought into engagement with a trip-finger 85, on the forward end of the pawl 80, sufficiently to 125 depress this pawl out of engagement with the notch 81, and since the slide-bar has already been released by the pawl 78, the spring 72 will then draw it forward, thus causing one adding-wheel to be rotated through one additional space, correspond- 130 ing to the 1 which should be carried up from the adding-wheel next below. The opera- 135 tion of this carrying-mechanism is such that in case the amount carried, for example, from the wheel 31 to the wheel 32 happens to turn the latter wheel through the space from 9 to 0, the wheel 32 will cause the re- 140 lease of the next succeeding carrying-mech- 145 anism and thus carry a unit to the wheel 33, and thus, in fact, all of the carrying-mech- 150 anism may operate in rapid succession, if necessary, after the completion of the re- 155 turn-movement of the impressing-mech- 160 anism. Whenever the carrying-mechanisms are so operated they are immediately reset, 165

upon the next impressing-movement of the machine, in the manner above described.

Since the adding-wheel 35 and the higher wheels in the series are rotated only by units carried from the lower wheels, these higher wheels may be actuated by any ordinary or suitable carrying-mechanism, such as the usual mutilated gear 87, on the rim of the wheel 34 in Fig. 3, and pinions 88 and 89 connecting this mutilated gear with gear-teeth on the adding-wheel 35.

In order that the adding-wheels may be reset to zero position whenever desirable, a series of knurled rollers 90 are journaled in front of the adding-wheels, in position to engage the knurled surfaces thereon, these rollers being accessible through openings in front of the casing, so that they may be rotated by hand. Each of the knurled surfaces on the adding-wheels, as shown in Fig. 4 in the case of the surface 42 on the wheel 32, is provided with a notch 91 so located that when the adding-wheel reaches zero position the engagement between the wheel and the roller will be interrupted, thus causing the wheel to be arrested automatically at zero position.

In order to prevent a too sudden movement of the bars 71 of the carrying-mechanism, when released by the pawls 80 and 83, the left-hand end of each bar is preferably formed as a piston 86 closely fitting a cylindrical bore in the frame of the machine, and this arrangement has the effect 35 of a dash-pot, which retards the return movement of the bars.

The general operation of the machine is as follows: The user places a check-blank upon the work-support 8, face downward, and so adjusts it as to bring beneath the platen 9 the line upon which the amount of the check is to be printed. The user then turns the hand-wheel 15 until the required number of dollars is visible through the sight-opening 117, and turns the hand-wheel 18 until the required number of cents is visible through the sight-opening 20. By the performance of these setting operations the several stop-plates 65 and 66 are brought to the positions in which they will suitably control the subsequent movement of the adding-mechanism. The user then depresses the hand-lever 10, thus causing the platen to press the paper against the types which have been brought selectively to the opening in the work-support. During this downward movement of the hand-lever any of the carrying-bars 71 which have previously operated are returned to rearward or normal position, and at the same time the gear-segments 63 are all released, so that they are swung upwardly by the springs 53, to an extent determined by the several stop-plates. The user immediately releases the hand-lever 10 after the production of an

impression, whereupon the impressing-mechanism returns to normal position by a movement which is retarded by the dash-pot. During this return-movement all of the gear-segments 63 are swung back by 70 the arms 45 to their normal position, thus producing rotative movement of the several adding-wheels according to the extent of movement of the corresponding gear-segments. Finally, as the impressing-mechanism and the arms 75 return fully to normal position, the pawls 80 are all depressed, and the carrying-mechanism then operates in the case of any of the wheels to which a unit should be carried from the next wheel 75 below, as determined by the positions of the trip-pins 84, the trip-arms 83, and the pawls 78. While the operations above described, except for the placing of the blank and the setting of the type-wheels, occur 80 always in the described sequence, the time occupied by these operations is very slight, so that no interval between them is appreciable by the operator of the machine, and the movements of the impressing-mechanism are not sufficiently retarded to diminish 85 the practical speed of operation of the machine as a whole.

My invention is not limited to the embodiment thereof hereinbefore described and 90 illustrated in the accompanying drawings, but it may be embodied in various other forms within the nature of the invention as it is defined in the following claims.

I claim:—

1. The combination, with a printing-machine comprising a type-carrier movable to bring various types selectively into operative position, and impressing-mechanism movable to cause an impression from said types, of adding-mechanism, means, actuated by connection with the impressing-mechanism, for moving the adding-mechanism, and means, actuated by the selective movement of the type-carrier, for determining the extent of movement imparted to the adding-mechanism.

2. The combination, with a printing-machine comprising a type-carrier manually movable to bring various types selectively into operative position, and impressing-mechanism manually movable to cause an impression from said types; of adding-mechanism, means, actuated by connection with the impressing-mechanism, for moving the adding-mechanism; and a series of graduated stops movable selectively into position by the selective movement of the type-carrier, and co-operating with the means for moving the adding-mechanism to determine 115 the extent of movement imparted to said mechanism.

3. The combination, with a printing-machine comprising a manually-rotatable type-carrier provided with a peripheral series o

types expressive of various amounts, a platen for pressing a blank into engagement with the types, and manually-operable means for actuating the platen; of a set of adding-wheels; means, connected with the platen-actuating mechanism and actuated thereby, for rotating the adding-wheels; and a graduated stop-plate rotatable with the type-carrier and adapted to arrest the movement of the means by which the type-wheels are rotated after varying degrees of movement corresponding with the respective amounts indicated by the types on the type-carrier.

15 4. The combination, with a printing-machine comprising a type-carrier manually movable to bring various types selectively into operative position, and impressing-mechanism manually movable to cause an impression from said types; of adding-mechanism; means, including an actuating-spring, for actuating the adding-mechanism; means, actuated in connection with the type-carrier, for determining the degree 20 of movement imparted to the adding-mechanism by its said actuating-means; a setting-spring; mechanism, connected with the impressing-mechanism and with the actuating-means of the adding-mechanism, for tensing

the setting-spring and simultaneously releasing said actuating-means; and means for retarding the return-movement of the setting-spring and the connecting-mechanism while the actuating-spring is moving the counting-mechanism.

35 5. The combination, with a printing-machine comprising a type-carrier movable manually to bring a series of types selectively into operative position, and impressing-mechanism manually movable to cause an impression from said types; of adding-mechanism; spring-actuated means for moving the adding-mechanism; spring-actuated means, connected with and controlled by the impressing-mechanism, for releasing the adding-mechanism-actuating means upon an operative movement of the impressing-mechanism, and for resetting said means upon the return-movement of the impressing-mechanism; and means for retarding 40 said return-movement during the operative movement of the adding-mechanism-actuating means.
